(57) **CLAIM**

The ornamental design of a panel of an evaporative cooler, as shown and described.

DESCRIPTION

FIG. 1 is a top, front, and right side perspective view of a panel of an evaporative cooler showing my new design;

FIG. 2 is an additional enlarged top, front, and right side perspective view thereof;

FIG. 3 is an enlarged front elevation view thereof; and,

FIG. 4 is an enlarged right side elevation view thereof, the left side being a mirror image of that shown.

The broken-line disclosure of the remainder of the evaporative cooler in FIG. 1 and the broken-line fragments of the remainder of the evaporative cooler in FIGS. 2-4 are shown for illustrative purposes only and form no part of the claimed design.
